UNITED STATES PATENT OFFICE

157,635

PANEL FOR TELEVISION RECEIVING SETS

William J. Schnell, Wilmette, Ill., assignor to Sentinel Radio Corporation, Evanston, Ill., a corporation of Illinois

Application December 27, 1948, Serial No. 150,369

Term of patent 14 years

(Cl. D56—4)

To all whom it may concern:

Be it known that I, William J. Schnell, a citizen of the United States, residing at Wilmette, Cook County, Illinois, have invented a new, original, and ornamental Design for a Panel for Television Receiving Sets, of which the following is a specification, reference being had to the accompanying drawings, forming a part thereof:

Fig. 1 is a front view of a panel for television receiving sets, showing my new design;

Fig. 2 is a side view of the right side of Fig. 1.

I claim:

The ornamental design for a panel for television receiving sets, as shown.

WILLIAM J. SCHNELL.
